(57) **CLAIM**

The ornamental design for a bottle closure, as shown and described.

DESCRIPTION

FIG. 1 is a perspective view of the bottle closure according to the invention;

FIG. 2 is a side view of the bottle closure of FIG. 1;

FIG. 3 is a rotated and perspective side view of the bottle closure of FIG. 1; and,

FIG. 4 is an opposite end perspective view of the bottle closure of FIG. 1.

Note that the area surrounded by dashed lines in the central area of the bottle closure forms no part of the claimed design of the present invention.
